HONING MACHINE

John E. Kline, Grosse Pointe Farms, Mich., assignor to Micromatic Hone Corporation, Detroit, Mich., a corporation of Michigan

Application November 27, 1939, Serial No. 306,208

10 Claims. (Cl. 51—34)

This invention relates to grinding or honing machines, and especially to mechanism for individually and collectively controlling the abrading tools of a multiple spindle machine.

The principal object of the invention is to improve the art of grinding machines.

It is also an object of the invention to provide control means for each abrading tool of a multiple spindle machine for causing such tool to effect operation for which it is set and then to cause contraction of the abrading head of each tool upon completion of such operation.

A further object is to provide individual control means for each abrading tool of a multiple spindle machine which renders each tool effective until the predetermined operation for that tool has been completed, and then retracts all of the abrading tools when the desired operations have been effected.

Another object is to provide each abrading tool of a multiple spindle machine with a working expansion limiting means for maintaining each tool effective until full limit expansion operation for which it has been set is completed, in conjunction with control means for retracting all tools when all operations for which the tools are preset have been effected, and further, to provide each tool with manually adjustable positive stop expansion limiting means effective as a safety stop for limiting expansion of the tool to a slightly greater amount in the event that the working expansion limiting means fails to operate.

Other objects, features, and advantages become apparent from the following description and appended claims.

For the purpose of illustrating the genus of the invention, a typical concrete embodiment is depicted in the accompanying drawings, in which:

Figure 1 is a perspective view of a multiple spindle grinding machine constructed in accordance with the principles of this invention;

Fig. 2 is a side elevation of one of the tool spindles which engages a centering and guiding bracket;

Fig. 3 is an enlarged side elevation with parts broken away and shown in section of the upper portion of one of the tool spindles depicted in Fig. 1;

Fig. 4 is a view similar to Fig. 3, of the lower portion of the abrading head of the tool shown in Fig. 2, the sectioned portion being taken substantially on the line 4—4 of Fig. 5;

Fig. 5 is a horizontal section taken substantially along the line 5—5 of Fig. 4;

Fig. 6 is a central vertical section taken 55

through drive and control means of one of the spindles depicted in Fig. 1, and associated parts being shown in elevation or in partial section;

Fig. 7 is a diagrammatic view illustrating the control system for the multiple spindle grinding machine depicted in Fig. 1;

Fig. 8 is a central vertical section of parts shown at the lower end of Fig. 3, the section being taken at approximately right angles to the partial section shown in Fig. 3; and,

Fig. 9 is an enlarged diagrammatic illustration of switch mechanism shown in Fig. 7.

Referring especially to Fig. 1 of the drawings, there is illustrated a workpiece in the form of an engine block 10, having a plurality of cylinder bores 11 which are to be ground, honed, or polished, such workpiece being indicative of any multiple cylinder block of a gas engine, steam engine, compressor, or similar apparatus adapted to be held in stationary position on an appropriate support of the machine illustrated and by any suitable fastening means, not shown. The abrading machine comprises an upright column 12 terminating at its upper end in a main housing 13 and having auxiliary housings 14 and 15 extending forwardly for housing spindle drive mechanism. Journalled in a reciprocating head or carriage 16 are a plurality of spindles 17, each comprising a driving portion 20, manually adjustable expansion stop means 21, and an abrading head 22. A guiding bracket 23, preferably integrally built into the work holding fixture for the workpiece 10, is provided for centering and guiding the abrading tools into the bores 11 of workpiece 10. An hydraulic cylinder 24 is disposed between the auxiliary housings 14 and 15 for moving the reciprocating carriage or head 16 toward and away from the workpiece for the purpose of moving the abrading tools into and out of the bores 11 of such workpiece 10.

Reference may now be had to Figs. 2 to 5 and 8, in which the numeral 25 represents the body of the head portion 22 of the abrading tool and such body is provided with an axial bore 26, a plurality of radial longitudinally extending grooves 27 extending through the body 25. A double cone expander 28 is axially movable within the bore 26 and makes a two-point contact at points 30 with stone holder 31, each of the holders 31 carrying a stone 32 provided with end clips and maintained in assembled relation with respect to the stone holder by means of bands or garter springs 33. The pitch of the double cone expander is beyond the angle of reversibility, allowing the expansion mechanism to advance the

cone, but preventing any amount of external pressure on the stones from reversing this action. This, in conjunction with the two-point contact of the stone holder, assures straight cylinders and prevents the stones from following tapered or irregular bores. The upper end of the body 25 is externally threaded and secured by means of a rocker connection to the shank 34. The rocker connection comprises a threaded sleeve 25, lock nut 36, a socket ring 37, and ball and socket portions 38 formed on shank 34 and body 25. The upper end of the double cone 28 is connected by means of a universal joint 40 to a spindle 41. The rocker connection between the shank 34 and the body 25, in conjunction with the universal joint 40, permits uniform transfer of expansion pressure to the abrading tool and compensates for slight misalignment of the work with relation to the axis of the machine spindle.

Referring more especially to Figs. 3 and 8, the upper end of the spindle 41 is depicted as threadedly connected to a holder 42 for a pin 43 which projects through the slot 44 of the shank 34 and into an adjusting sleeve 45. The sleeve 45 is externally threaded and threadedly engages a knurled adjusting nut 46. The nut 46 supports a sleeve 47 through anti-friction members 48. A ball 50 is biased upwardly into one of a series of apertures in the lower end of the sleeve 47 by springs 51 retained by studs 52 for locking the nut 46 against accidental rotation. The anti-friction members 48 are maintained in position by a sleeve 53 pinned to the sleeve 47 by pins 54. A pin 55 fixed to the sleeve 47 extends through a slot 56 provided in the shank 34, the gap between the pin 55 and the base portion of the slot 56 constituting the safety positive stop limiting means for regulating the expansion of the abrading tool in the event of failure of the working expansion limiting means, later described, to function.

The stop gap may be adjusted by rotating the knurled adjusting nut 46 which, due to its threaded engagement with the adjustment sleeve 45, opens or closes the gap between the lower surface of the pin 55 and the bottom of the slot 56. Such positive stop expansion limiting means of the abrading tool is intended to be set slightly beyond the working stop limiting means, to be explained later, and to be employed only as a safety means to prevent grinding or honing a cylindrical opening materially oversize. The upper bore of the shank 34 is enlarged slightly to provide a shoulder 57 adapted to support the lower end of a recoil spring 60, the upper end of which abuts a pin 55 to effect contraction of the abrading tool head when compression on the expanding means, later described, is relaxed.

The driver 20 of the abrading tool includes a universal joint 61 and is connected to the upper end of the shank 34 by a pin 62 adapted to be maintained in assembled relation with respect to the driver and shank 34 by a sleeve 63 which is locked in position by a spring pressed detent 64. As previously indicated, the head assembly 22 contains all the expansion actuating and adjusting units, and the expansion of the abrading stones 32 is effected by hydraulic pressure on the push rod 65 by fluid pressure mechanism in the reciprocating carriage or head 16, depicted in Fig. 1. This actuating pressure, carried through the center of the driver 20, automatically actuates the drive shaft push rod 66 and advances the double cone expander 28 through the adjustment mechanism included in the adjusting

unit, indicated generally at 21. A slot 67 is cut through the drive shaft push rod 66 to permit axial movement of the latter without interference with the pin 62.

Referring more specifically to Figs. 3, 4, 5, and 7, the shank 34 is provided with one, while the body 25 is provided with a plurality, of longitudinally extended passages 18, three such passages being illustrated in the body 25, leading to a corresponding number of outlet nozzles 19 extending radially outwardly from the approximately longitudinal center of the body 25 and spaced equidistantly about its periphery. These nozzles extend outwardly lesser distances than that of the normal extension of the stones 32. The passage 18 opens outwardly through the shank 34 to an annular recess 29 which is arranged to register with a similar recess 39 in a collar 49 rotatably journaled on the shank between the driver 20 and the adjusting unit 21. A spacer collar 59 fixed to the shank 34 between the collar 49 and the sleeve 47 of adjusting unit 21, maintains the collar 49 in the desired position axially of the tool spindle and the recesses 29 and 39 in registry. A fitting 68 and a flexible conduit 69 lead from the registering recesses 29 and 39 for purposes described hereinafter.

Reference may now be had to Figure 6, which illustrates the fluid pressure responsive mechanism individual to and designed for effecting expansion of each abrading tool, and further depicts control means for such fluid pressure responsive mechanism and the rotating guide mechanism for each tool spindle. Each abrading tool is rotatably driven by means of a gear 70, keyed at 71 to a drive shaft 72, which is journaled by means of thrust bearings 74 to the reciprocating carriage or head 16. The gears 70 are driven from spindle drive mechanism housed within the auxiliary housings 14 and 15 of the abrading machine illustrated in Fig. 1. The gear sleeve 72 is threaded at its lower end and clamped to the driver 20 by means of the clamping sleeve 75 which threadedly engages the lower end of gear sleeve 72. Cylindrical bores 76 are provided in the upper portion of the reciprocating carriage or head 16 in axial alignment with the axes of each of the tool spindles. A piston 77 is disposed in each of the cylinders 76 and is provided with a downwardly and axially extending stem 78 adapted to transmit pressure from the fluid compression chamber 80, which lies between the piston 77 and the closed or blind end of the cylinder 76, to the upper end of the push rod 65 for the purpose of expanding the abrading tool 22. Each piston stem 78 is provided with an enlarged portion 81, projecting through a stuffing box 82 which seals and closes the lower end of its cylinder 76. This arrangement also provides a fluid pressure expansion chamber 83 between the stuffing box 82 and the lower end of the piston 77, so that when fluid pressure within the latter chamber exceeds that in the fluid pressure chamber 80, the piston 77 will elevate and allow the recoil spring 60 (Fig. 3), to collapse the head 22 of the abrading tool. A solenoid operated valve, indicated generally at 84 in Fig. 6, controls the admission of fluid pressure to the compression chambers 80 and 83 disposed at opposite ends of each piston 77. Each valve 84 comprises a cylindrical casing 85 provided with a central bore 86, which in turn is provided with five substantially equally spaced annular grooves 87. A return passage 88 connects the extreme right and left hand annular grooves 87 with each other, but

communicates with none of the other annular passages 87. A return conduit 90 leads from the fluid return passage 88 to the source of fluid pressure, as indicated in Fig. 7. A plunger 91 provided with a pair of spaced piston portions 92 is disposed in the bore 86, with the pistons 92 so spaced that when the plunger 91 is moved to the extreme right or left hand positions within the bore 86, one piston will shut off communication between the adjacent outside annular grooves 87 at one end of the bore 86, while the adjacent outside annular grooves 87 at the other end of the bore 86 will be in communication with each other, and the centrally arranged annular grooves 87 will be in communication with the next adjacent annular grooves on the first-mentioned end.

As illustrated in Fig. 6, the plunger 91 is moved to its extreme left-hand position with the left-hand piston 92 closing communication between the adjacent grooves at the left-hand end of the bore 86, and with the next to left-hand groove 87 in communication with the central grooves 87, while the right-hand piston 92 closes the central groove 87 with respect to the next right-hand groove 87 and the latter groove is in communication with the extreme right-hand groove 87. A conduit 93 communicates with the next to left-hand annular groove 87 and with the fluid pressure chamber 80 while a conduit 94 communicates with the next to right-hand annular groove 87 and the fluid pressure chamber 83. A pressure supply conduit 95 communicates between the pressure fluid source and the central annular groove 87. Thus, with the plunger 91 in the position indicated, pressure fluid will flow from the conduit 95 through the central annular groove 87 to the next left-hand annular groove 87, and through the conduit 93 to the fluid pressure chamber 80, and force the piston 77 downwardly to expand the abrading tool. At this time, the left-hand piston 92 cuts off communication between the left-hand groove 87 and the next to left-hand groove 87, so that there will be flow between the pressure supply and the return line, and the right-hand piston cuts off communication between the central annular groove 87 and the next right-hand annular groove. The latter annular groove, however, is in open communication with a right-hand annular groove 87 and the return passage 88, so that pressure chamber 83 will be in communication through the conduit 94 and the return passage 84 with the return line 90. Movement of the plunger 91 to the extreme right-hand position will place compression chamber 83 in communication with the pressure supply conduits 95 and the pressure chamber 80 in communication with return line 90. This will effect elevation of the piston 77 and allow the recoil spring 60, indicated in Fig. 2, to cause contraction of the head of the abrading tool.

Solenoids 96 and 97 are provided at the right and left-hand ends, respectively, of valve 84, as indicated in Figs. 6 and 7, and in the illustrated position, solenoid 97 is energized while solenoid 96 is in de-energized condition and pressure supply conduit 95 is in communication with pressure chamber 80 to effect expansion of the abrading tool.

The working expansion limiting means for each abrading tool is controlled by a pressure responsive means 73 and a micro switch 105. A plunger 100 of the pressure responsive means 73, normally biased by means of a spring 101 away from the micro switch 105, is arranged in a suitable cylinder 98 provided on the recip-

rocating carriage or head 16, and is provided with a stem 102 which projects through a threaded adjusting plug 103, the latter being maintained in adjusted position by virtue of its threaded engagement with the cylinder 98. The plug 103 is adapted to be adjusted to regulate the force exerted upon the plunger 100 by the spring 101, so that the latter, at the proper time, operates the micro switch 105 when the piston 77 has descended the proper amount to effect the desired expansion of the abrading tool.

Reference may now be had to Figs. 7 and 9 which depict a control system for the reciprocating carriage 16 and the six abrading tool spindles carried thereby. As indicated in Fig. 7, a micro switch 105 is provided for each of the tool spindles and each micro switch 105 controls the operation of a piston 77 through a solenoid operated valve 84, but a single piston and solenoid operated valve being illustrated. Fig. 9 illustrates diagrammatically the two left-hand micro switches 105 and the extreme right-hand micro switch 105 shown in Fig. 7. Each of the switches 105 includes a pair of stationary contacts 106 and 107 mounted on a base plate 108, and adapted to be contacted by a terminal contact 110 carried by a snap spring conductor 111, which normally maintains the contact 110 in engagement with the stationary contact 106. The snap spring conductors 111 are all connected by conductors 112 to a power line 113 leading to a suitable source of electrical energy, not shown. Another power line 112 leads to one terminal of each of the solenoids 96 and 97 of each solenoid operated valve 84. The stationary contacts 106 are connected by conductors 114 to the remaining terminals of the solenoids 97 while the stationary contacts 107 are connected by means of conductor 115 to the remaining terminals of solenoids 96. A stationary contact 116 is mounted on each switch board 108 of the micro switches 105 and is adapted to be engaged by a contact 117 carried by the snap spring conductor 111 when the terminal contact 110 engages the stationary contact 107.

The end portions of snap spring conductors 111 are forced longitudinally inwardly toward the center of such conductor to place the same in a bowed condition between the pivots 119, so as to cause contacts 110 to engage contact 106, or to engage contacts 110 with contacts 107 and contacts 117 with contacts 116. The contacts 117 are insulated by means of dielectric pads 118 from the snap spring conductors 111. The contacts 117 of the extreme right-hand micro switch 105 is connected by means of a conductor 120 to one terminal of the winding or solenoid 121, the remaining terminals of the coil of solenoid 121 being connected by means of a conductor 122 to power line 112. The stationary contacts 116, except for that of the left-hand switch 105, are each connected to the contacts 117 of the next connector switch to the left, as viewed in Figs. 7 and 9. The contact 116 of the left-hand micro switch 105, as viewed in Figs. 7 and 9, is connected by means of a connector 123 with the power line 113. Each micro switch 105 is operated by a switch actuating plunger 124 provided with two insulated pegs 125 and these plungers are adapted to be actuated by springs 126 to snap the spring conductor 111 to the left, as viewed in Figs. 7 and 9, in order to break contact between the terminal contacts 110 and stationary contacts 106 and cause the terminal contacts 110 to engage the stationary contacts 107.

and also at the same time to cause the contacts 117 to engage the stationary contacts 116.

As indicated in Fig. 7, the solenoid 121 is adapted to operate a valve 126, which controls the admission of fluid under pressure to either end of the cylinder 24 for lowering or elevating the reciprocating carriage or head 16. It is noted that the solenoid 121 is energized only when all of the micro switches 126 have operated to snap the spring conductors 111 to the left-hand position, as viewed in Figs. 7 and 9. Such left-hand position is indicated by the broken line position of snap spring conductor 111 of the extreme left-hand switch, as indicated in Fig. 9. This closes the circuit from the power line 112 to the coil of solenoid 121, conductor 120, contacts 117 and 116 of all of the micro switches, and conductor 123, completing the circuit to the other power line 113. Energization of the solenoid 121 causes it to operate the valve 126, so that the hydraulic cylinder 24 will elevate the reciprocating carriage or head 16 to remove the abrading tools from the workpiece and guide bracket 28. The valve 126 may be operated in the opposite direction by spring, gravity, or other desired means, to cause the hydraulic cylinder 24 to lower the reciprocating head 16.

A pump 130 is interposed in the pressure conduit 95 between a fluid tank 131 and the solenoid operated valves 84. A return conduit 90 leads the fluid back to the tank 131. The pressure conduit 132 leads from the pressure conduits 95 at a point between the pump 130 and the solenoid operated valves 84 to the control valve 126 for hydraulic cylinder 24. A return line 133 leads from the fluid pressure line 132 back to the tank 131, and a pressure regulator 134 may be interposed in this return line for regulating the pressure of the fluid supply to the control valve 126. A pressure regulator 135 may also be interposed in the pressure conduit 95 between the pump 130 and the solenoid operated valve 84, the return conduit 136 leading from the pressure regulator 135, to the return conduit 90. A motor 137, or other suitable driving means, is provided for operating the pump 130.

Air is supplied at a comparatively high but constant pressure through a conduit 140 to supply air under pressure to the pressure responsive means 73 and through the flexible conduit 69, fitting 68, and rotatably journaled collar 49, to the longitudinal passage 18 in shank 34 and nozzles 19 of the passage 18 in the body 25. The air may be supplied to the conduits 140 by any suitable source of supply, not shown, high air pressures being employed since these are susceptible to comparatively close pressure regulation. A pressure reducing valve 141 is interposed in the conduit 140 and just beyond the pressure reduction valve 141, a pressure gauge 142 is provided for indicating the reduced pressure. A volume control valve 143 is interposed in the conduit 140 and this is followed by a pressure gauge 144 to indicate the pressure to which the air has been reduced after passing through both the pressure reducing valve 141 and the volume control valve 143.

The conduit 140 leads from the pressure gauge 144 to a T-union 145 and the latter communicates both with the pressure responsive means 73 and the flexible conduit 69.

During operation of the abrading machine, the tool spindles 17 are rotated through gears 10 and the spindle drive mechanism contained within the housing 14 and 15. Fluid under

pressure, supplied from the tank 131 by means of pump 130, acts through the control valve 126, solenoid 121 being deenergized at this time, to lower the spindle head 16 and lower the tool spindles 17 through the guiding bracket 23 to the bores 11 of workpiece 10. Fluid under pressure is also supplied from the pump 130 through the pressure conduit 95 to the solenoid operated valves 84 and conduits 93 to the pressure chambers 80 for each of the tool expanding pistons 77 in order to effect expansion of the abrading tool head 22. At this time, all of the micro switches 105 are in the positions indicated in Fig. 7 and in the full line positions indicated in Fig. 9 with the solenoids 97 energized and the solenoid operated valves in the positions indicated in Fig. 6. The solenoids 97 are energized by the electrical circuit including the power line 112, the coil of solenoid 97, conductors 114, stationary contacts 106, terminal contacts 110, the snap spring conductors 111, and conductors 158 which lead to the power line 113. Fluid pressure within the pressure chambers 80 forces pistons 77 downwardly until each abrading tool head 22 has been expanded to the working limit for which the pressure responsive means 73 has been set. The pressure responsive means 73 is set by adjusting the spring tension of spring 101 by means of the screwthreaded plug 103. The spring 101 can force the piston 100 to the left, as viewed in Fig. 6, only when the air pressure supplied through the conduit 140 and through the pressure reducing valve 141 and volume control valve 143 drops sufficiently to permit the spring 101 to move the piston 100 to the left as viewed in Fig. 6. It is noted that the air pressure supplied to the left-hand end of piston 100, as viewed in Figs. 6 and 7, is vented only at the nozzles 19 in the tool head 25. As the cutting stone 32 increases the diameter of the cylindrical opening in the work piece 10, the clearance increases between the ends of the nozzles 19 and the bores of the cylindrical openings of the workpiece. When such clearance has reached a predetermined value, a greater amount of air escapes through the nozzles 19, through passages 18, collar 49, fittings 68 and flexible conduit 69 than is admitted through the volume control valve 143 thus causing a pressure drop upon the left-hand end of the piston 100, as viewed in Figs. 6 and 7, so that the spring 101 can move the piston 100 to the left and permit snapswitch 105 to operate.

In each snapswitch 105, the spring 138 causes the slide bar 124 to follow the movement of the piston 100 of the pressure responsive means 73 associated with that snapswitch. As soon as the pressure has dropped sufficiently at the left end of piston 100 of the pressure responsive means 73, movement of the piston to the left will allow the springs 138 of the associated snapswitch 105 to move the slide bar 124 to the left, as viewed in Fig. 9, so that a peg 125 on the slide bar 124 will force an intermediate portion of the snap spring conductor 111 past the dead center of pivot centers 119 and cause the snapswitch to assume the position indicated in broken lines. It is noted in this connection that the pegs 125 engage the snap spring conductors 111 at a point spaced farther from the lower pivot center 119 than from the upper pivot center 119, as indicated by the construction lines at the left-hand side of Fig. 9. In other words, the distance 146 is greater than the distance 147. This arrangement of the snap spring conductors 111 and slide bars 124 causes the snap spring conductors to

maintain the terminal contacts 110 firmly in engagement with the stationary contacts 106 until the snap spring conductors have been so thrown beyond dead center and throw the snap spring switches to the position indicated by broken lines at the left-hand side of Fig. 9. When a micro switch has been operated from the full line position to dotted line position, contact is broken between the stationary contact 106 and terminal contacts 110 which severs the circuit for the coil of solenoid 97 thus de-energizing the solenoid. The micro switches 105 are operated individually as soon as the abrading tool associated with each switch has enlarged its respective work bore sufficiently to provide the predetermined clearance between the nozzles 19 and the bore of the cylinder cut in the workpiece thus causing a sufficient venting in the air pressure system to permit the pressure responsive means 73, individual to the abrading tool, to cause its piston 100 to move sufficiently to the left so that its associated micro switch 105 will operate. Operation of a micro switch brings the terminal contact 110 into engagement with stationary contacts 107 in order to energize the solenoid 96 through the power circuit including the power line 112, the coil of solenoid 96, conductors 115, stationary contacts 107 snap spring conductor 111, and conductor 58 to the power line 113. As soon as all of the micro switches 125 have been thrown to the left-hand positions, broken line positions indicated in Fig. 9, the circuit is closed between the power line 113 through the conductor 123 of the extreme left-hand micro switch 105 to the contact 117 which at this time engages the stationary contact 116 of that switch and thence through all of the contacts 117 and 116 of the other switches to the conductor 120, and then through the winding of the solenoid 121 to the power line 112. This effects energization of solenoid 121 and reverses the action of the control valve 126 causing the hydraulic cylinder 24 to elevate the spindle head 16. Energization of the solenoid 96 has in the meantime caused fluid pressure delivered from the pump 130 through the solenoid operated valves 84 and conduit 94 to the pressure chamber 83 to elevate the piston 77 in order to cause contraction of the tool heads 23 prior to their withdrawal from the bore 11 of workpiece 10.

As many changes could be made in the above described construction, and many apparently widely different embodiments of this invention could be had without departing from the spirit and scope thereof, it is intended that all matter contained in the above description or shown in the accompanying drawings shall be interpreted as illustrative and not in a limiting sense.

What is claimed is:

1. In a grinding or honing machine, in combination, a reciprocating tool support, means for reciprocating, said support, a spindle journalled at one end in said support and carrying at its other end an expansible and contractible abrading tool, means for rotating said tool, means for expanding and contracting the abrading tool, fluid pressure responsive means for controlling the operation of said tool expanding and contracting means, a valve for reversing the action of the tool expanding and contracting means and a source of pressure fluid communicating with said fluid pressure responsive means and discharging in the periphery of said abrading tool whereby a predetermined pressure drop at the abrading tool causes the pressure responsive

means to operate said valve and reverse the action of the tool expanding and contracting means.

2. In a grinding or honing machine, in combination, a reciprocating tool support, means for reciprocating said support, a spindle journalled at one end in said support and carrying at its other end an expansible and contractible abrading tool, means for rotating said tool, means for expanding and contracting the abrading tool, fluid pressure responsive means for controlling the operation of said tool expanding and contracting means, a plurality of discharge nozzles in the periphery of said abrading tool, and a source of pressure fluid communicating with said pressure responsive means and with said discharge nozzles, whereby a pressure drop occurring as a result of a predetermined amount of clearance between the nozzles in the abrading tool and the bore of the workpiece cut by the abrading tool causes the pressure responsive means to limit the expanding action of the tool expanding and contracting means.

3. In a grinding or honing machine, in combination, a reciprocating tool support, means for reciprocating said support, a spindle journalled at one end in said support and carrying at its other end an expansible and contractible abrading tool, means for rotating said tool, means for expanding and contracting the abrading tool, fluid pressure responsive means for controlling the operation of said tool expanding and contracting means, a plurality of discharge nozzles in the periphery of said abrading tool, a substantially constant pressure source of pressure fluid communicating with said pressure responsive means and with said discharge nozzles, and pressure reducing means interposed between said source and said pressure responsive means whereby a predetermined pressure drop at the nozzles causes the pressure responsive means to limit the expanding action of the tool expanding and contracting means.

4. In a grinding or honing machine, in combination, a reciprocating tool support, means for reciprocating said support, a spindle journalled at one end in said support and carrying at its other end an expansible and contractible abrading tool, means for rotating said tool, means for expanding and contracting the abrading tool, fluid pressure responsive means for controlling the operation of said tool expanding and contracting means, a plurality of discharge nozzles in the periphery of said abrading tool, a substantially constant pressure source of pressure fluid communicating with said pressure responsive means and with said discharge nozzles, and a plurality of pressure reducing means interposed in series between said source and said pressure responsive means, whereby a predetermined pressure drop at the nozzles causes the pressure responsive means to limit the expanding action of the tool expanding and contracting means.

5. In a grinding or honing machine, in combination, a reciprocating tool support, a spindle journalled at one end in said support and adapted to carry at its other end an expansible and contractible abrading tool, tool adjusting means on said support including expansible and contractible fluid pressure responsive means for expanding and contracting the abrading tool, a source of pressure fluid for said fluid pressure responsive means, valve means for directing pressure fluid from said source selectively into either

end of said fluid pressure responsive means selectively to expand or contract the abrading tool, a second source of pressure fluid, a second pressure responsive means communicating with said second source of pressure fluid, and a vent means in said abrading tool communicating with said second source of fluid pressure whereby a predetermined drop in the pressure applied to said second fluid pressure responsive means causes the operation of said valve means.

6. In a grinding or honing machine, in combination, a reciprocation tool support, a spindle journaled on one end of said support and adapted to carry on its other end an expansible and contractible abrading tool, tool adjusting means on said support including an expansible and contractible fluid pressure responsive means for expanding and contracting the abrading tool, and source of pressure fluid for such fluid pressure responsive means, valve means for directing pressure fluid from said source selectively into either end of said fluid pressure responsive means selectively to expand or contract the abrading tool, a second source for pressure fluid, a second pressure fluid responsive means communicating with said second source of pressure fluid, and vent means in said abrading tool communicating with said second source of pressure fluid and said second pressure fluid responsive means, whereby a predetermined drop in pressure applied to said second fluid pressure responsive means causes the latter to reverse the operation of said valve means.

7. In a grinding or honing machine, in combination, a reciprocating tool support, a spindle journaled at one end on said support and adapted to carry on its other end an expansible and contractible abrading tool, tool adjusting means on said support including a hydraulic cylinder, a piston in said cylinder, means operable by said piston for expanding and contracting the abrading tool, a source of pressure fluid for said cylinder, valve means for directing the pressure fluid from said source into either end of said cylinder selectively to expand or contract the abrading tool, a second source of pressure fluid, a second pressure responsive means communicating with said second source of pressure fluid, and a vent means in said abrading tool communicating with said second source of fluid pressure whereby a predetermined drop in the pressure applied to said second fluid pressure responsive means causes the said second pressure responsive means to operate said valve means and cause it to reverse.

8. In a grinding or honing machine, in combination, a reciprocating tool support, a plurality of spindles each journaled at one end on said support and adapted to carry on its other end an expansible and contractible abrading tool, a tool adjusting means for each tool on said support including expansible and contractible fluid pressure responsive means for expanding

and contracting each abrading tool, the source of fluid pressure for all of said fluid pressure responsive means, a valve means for each of said fluid pressure responsive means for directing pressure fluid from said source selectively into either end of each of said pressure responsive means to expand or contract one of the abrading tools, the second source of fluid pressure, a second pressure responsive means individual to each tool 10 and communicating with said second source of pressure fluid, and vent means in each abrading tool communicating with the said second source of said pressure fluid whereby a predetermined drop in the pressure applied to the said second 15 pressure responsive means individual to that tool causes the said responsive means to reverse the operation of the valve means individual to that tool.

9. In a grinding or honing machine for finishing a plurality of cylindrical surfaces in a workpiece, a reciprocating tool support, means for moving said support toward and away from the workpiece, a plurality of spindles each journaled at one end on said support and adapted to carry 20 on its other end an expansible and contractible abrading tool, a tool adjusting means on each tool on said support including expansible and contractible fluid pressure responsive means for expanding and contracting each abrading tool, a source of pressure fluid for all of said fluid pressure responsive means, a valve means for each of said fluid pressure responsive means for directing pressure fluid from said source selectively into either end of each of said pressure 25 responsive means to expand or contract one of the abrading tools, a second source of pressure fluid, a second pressure responsive means individual to each tool and communicating with said second source of pressure fluid, vent means in 30 each abrading tool communicating with the said second source of pressure fluid whereby a predetermined drop in the pressure applied to said second fluid pressure responsive means individual to that tool causes said second fluid pressure responsive means to produce a reversal of the operation of the valve means individual to that tool, and means operable in response to such reversals of operation of all valve means for causing the first named means to move said support away from the workpiece.

10. In a honing machine for finishing the wall of a cylinder, a reciprocable tool support, a spindle journaled in said support, means for reciprocating said support, means for rotating said spindle, a tool having an expansible honing element, means for securing said tool in said spindle, a pressure fluid system in said tool including a jet which is set relative to the desired diameter to be machined, and means responsive to changes 55 in pressure in said system for indicating when the diameter has been reached.
